UNITED STATES PATENT OFFICE.

JOHN SCHREIBER, OF ST. LOUIS, MISSOURI.

SEWING MACHINE.

Original application filed May 21, 1921, Serial No. 471,314, Patent No. 1,440,556, dated January 2, 1923.
Divided and this application filed December 11, 1922. Serial No. 606,083.

This invention relates to sewing machines, and has special reference to the presser foot mechanism.

An object of the invention is to provide an efficient presser foot mechanism for use in sewing machines that are designed and adapted for thick and heavy work, such as sewing machines for use in manufacture of harness, shoes, etc.

10 The subject-matter of the present invention is divided from my prior application Serial No. 471,314, filed May 21, 1921, patented January 2, 1923, No. 1,440,556, and an additional object of the invention is to 15 provide presser foot equipment for the sewing machine of my said prior application for holding the work upon the work plate and for releasing the work for lateral movement during the operation of the machine.

20 In the drawings, Fig. 1 is a front elevation of the machine with the thread feeding attachment removed and showing my improved presser foot mechanism.

Fig. 2 is a side elevation of the presser 25 foot mechanism.

Fig. 3 is a sectional view showing the brake release device.

The machine in connection with which the present invention is shown comprises a 30 front head frame 1 at the forward end of which the work supporting plate 2 is located for supporting the work in position to receive stitches formed by the stitching mechanism of which the needle 3 is a part.

35 The presser foot 4 extends from a rocking supporting member which comprises a ring 5 supported for rocking movements on a boss 6 extending from one wall of the front head frame 1. A rod 7 has its forward end 40 pivoted to the presser foot support 5 so that forward movement of said rod will lower the presser foot 4 to press the work on the work plate 2. The presser foot 4 extends downwardly and laterally from the 45 support 5 and has a slot therein to receive the needle 3. The rod 7 has its rear end supported within a sleeve 8 carried by a pivot support 9. The support 9 is swingingly supported by a pin 10 and is connected with an operating lever 11. The lever 11 embraces the support 9 between the arms of the fork at the lower end of said lever, and the connection between the lever 11 and the support 9 is pivotal. The axis of the pivot

12 connecting the lever 11 with the support 55 9 is at right angles to the axis of the pivot 10.

As shown in Fig. 2 the lever 11 is in its forward position and the presser foot 4 is raised. When the lever 11 is moved 60 rearwardly the spring 13, which encircles the rod 7 is placed under compression. The forward end of the spring 13 bears against a circumferential shoulder or washer 14 on the rod 7, and the rear end of said spring 65 bears against the sleeve 8. By this construction the presser foot 4 will be lowered and pressed upon the work between the presser foot and the work plate 2. At the proper time the spring 13 yields to permit the work 70 to be moved laterally during the stitching operations.

Before the time arrives for the work to be moved laterally upon the work plate 2 the presser foot 4 is held rigid upon the 75 work by a brake device or clutch provided for that purpose. This brake device or clutch comprises a brake shoe or clutch member 15 located within a groove or channel in the rear peripheral portion of the presser foot support 5. The brake shoe or 80 clutch device is pivoted on a support 16. An elongated slot 17 receives the support 16, forward movement of the brake device 85 on the support being limited by an adjustable abutment 18. The abutment 18 is in the form of a screw carried by the brake device and has its forward end serving as an abutment to contact with the support 16. The brake shoe operating lever is under 90 control of the lever 11, so that when the lever 11 is moved to its rear position the brake shoe operating lever will set the brake 95 member 15 to hold the presser foot positively and rigidly for the time. As shown, the brake 100 shoe operating lever comprises an arm 19 having its forward end pivoted on a support 20 and having its rear end supported upon a spring 21. A cam 22 on the forward end of the brake shoe operating lever 19 contacts with the brake shoe 15 and presses the brake shoe into rigid engagement with the presser foot support 5 when the rear end of the operating lever is raised by the spring 21. The brake shoe operating lever 19 has an arm 105 23 extending upwardly from the spring 21 and provided with an elongated part 24 on the upper end thereof constituting a con-

tact or abutment member for the roller 25 on the lower end of the pivoted support 9 that is controlled by the lever 11.

The support 9 and the arm 23 of the brake shoe operating lever, with the part 24 thereon, constitute a species of toggle whereby movement of the lever 11 will control the brake spring lever 19. When the lever 11 is in its rear position the support 9 is beyond the forward end of the part 24, permitting the spring 21 to raise the rear end of the lever 19 and cause the cam 22 to press the brake shoe 15 in rigid engagement with the presser foot support 5. The parts occupy the positions last described when the machine is in use, so that for certain desired operations the presser foot will hold the work rigidly upon the work plate 2. At the proper time, however, the brake is released to permit lateral movement of the work. This is accomplished by a roller 23 carried by the cam bar 27 passing over the pin or projection 28 on the brake shoe operating lever 19. As the roller 23 passes over the pin or projection 28 the spring 21 is compressed, thereby releasing the cam 22 from pressure against the brake shoe, and permitting the brake shoe to release the presser foot support. This permits the work to be moved laterally, the presser foot yielding to adjust itself to any irregularities in the thickness of the work, while the serrated work plate 2 prevents the work from slipping forwardly.

The spring 21 constitutes an elastic actuator for the brake shoe operating device. The tension of the spring may be varied by adjustment of the support 29, upon which the spring seat 30 is mounted. The spring 21 yields to the different mechanisms which operate to control the application and release of the brake shoe to and from the presser foot support. It will be understood that during the operation of the machine the brake shoe is held in set position against the presser foot support 5, except during the intermittent intervals in which the work is being shifted laterally. At the proper time in the forward movement of the cam bar 27, the brake shoe is released by operation of the roller 23 against the part 28. When the cam bar 27 is moved rearwardly the roller 23 is disengaged from the projection 28, permitting the spring 21 to reset the brake to hold the presser foot positively upon the work. These operations are repeatedly performed and as an incident to the operation of the machine and the timing of the operation is properly maintained throughout.

From the foregoing it will be seen that my invention is a highly efficient and satisfactory mechanism for use in a machine of the type for which it is designed. The construction and arrangement of the parts

may be varied in equivalent respects without departure from the nature and principle of the invention.

I do not restrict myself unessentially, but what I claim and desire to secure by Letters Patent is:—

1. In a sewing machine, the combination of a presser foot, a rod having one end pivoted to the presser foot, a spring encircling the rod, a lever, a sleeve supported by the lever and movable thereby to compress said spring and cause said spring to press the presser foot on the work, a brake, a pivot on which said brake is mounted, an additional pivot, a lever on said additional pivot for setting said brake to hold the presser foot on the work, and a spring for actuating said last-named lever to move said brake to and hold said brake in set position. 75

2. In a sewing machine, the combination of a presser foot, a rod having one end pivoted to the presser foot, a spring encircling the rod, a lever, a sleeve supported by the lever and movable thereby to compress said spring and cause said spring to press the presser foot on the work, a brake, a pivot on which said brake is mounted, an additional pivot, a lever on said additional pivot for setting said brake to hold the presser foot on the work, a spring for actuating said last-named lever to move said brake to and hold said brake in set position, and means operated by said first-named lever to release said second lever from said brake when said first lever is moved to position to release 100 said first spring from compression. 90

3. In a sewing machine, the combination of a presser foot, a spring for holding the presser foot on the work, a lever, a part supported by said lever for engaging and holding said spring under tension to press the presser foot on the work, a brake for holding the presser foot on the work, a support on which said brake is operated, an additional support, a lever pivoted on said additional support movable to and from position to set the brake against the presser foot, a spring for actuating said second lever to position to set the brake, and a device operating to release the brake intermittently 110 to permit the presser foot to yield while said first lever holds said first spring under compression. 115

4. In a sewing machine, the combination of a presser foot, a spring for holding the presser foot on the work, a lever, a part supported by said lever for engaging and holding said spring under tension to press the presser foot on the work, a brake for holding the presser foot on the work, a support on which said brake is operated, an additional support, a lever pivoted on said additional support movable to and from position to set the brake against the presser foot, a spring for actuating said second lever 125 130

to position to set the brake, a device operating to release the brake intermittently to permit the presser foot to yield while said first lever holds said first spring under compression, and means operated by said first lever for moving said second lever in opposition to said second spring to position to release the brake.

5. In a sewing machine, a pivoted presser foot, a spring, a support for said spring pivoted to the presser foot, a lever, an element supported by said lever engaging said spring and arranged to cause said spring to press the presser foot on the work when said lever is moved to one position, a brake settable to hold the presser foot on the work, a lever for setting said brake, a spring for actuating said lever to position to set said brake, and means operated by said first lever 10 to release said second lever from said brake when said first lever releases said first spring from tension and permitting said second spring to actuate said second lever to set

said brake when said first lever is in position holding said first spring under tension. 25

6. In a sewing machine, a pivoted presser foot, a spring, a support for said spring pivoted to the presser foot, a lever, an element supported by said lever engaging said spring and arranged to cause said spring to 30 press the presser foot on the work when said lever is moved to one position, a brake settable to hold the presser foot on the work, a lever for setting said brake, a spring for actuating said lever to position to set said 35 brake, means operated by said first lever to release said second lever from said brake when said first lever releases said first spring from tension and permitting said second spring to actuate said second lever to set 40 said brake when said first lever is in position holding said first spring under tension, and means for intermittently releasing said second lever from said brake while said first lever holds said first spring under tension.

JOHN SCHREIBER.
